CONVERTIBLE PEN-PLAYHOUSE

Samuel L. Dennis, Elizabethtown, N. C.

Application September 18, 1941, Serial No. 411,425

7 Claims. (Cl. 20-2)

This invention relates to a combined playpen and playhouse.

An object of this invention is to provide a combined playpen and playhouse which is constructed to simulate at least a portion of a log cabin.

Another object of this invention is to provide a playpen and playhouse wherein the front and rear walls thereof may be formed from slabs which are ordinarily waste lumber.

A further object of this invention is to provide a structure of this kind which may initially be erected as a playpen and playhouse, and which may be subsequently converted into only a playhouse.

A further object of this invention is to provide a structure of this kind which may be manufactured at a low cost and which may be constructed in wall sections which may be put together by an inexperienced mechanic or carpenter.

A further object of this invention is to provide a structure of this kind which may be placed at any convenient location in a yard and which may or may not be provided with a closed roof, the structure being provided with longitudinal rafters on which a fabric or other covering may be optionally placed.

A further object of this invention is to provide a structure of this kind which may be contracted from a combined playpen and playhouse to only a playhouse, and which is so constructed that the lumber taken out during the conversion of the structure may be used in fitting in certain portions of the playhouse, so that very little if any additional lumber will be required to make the conversion.

In the drawings:

Figure 1 is a detail front elevation partly broken away of a combined playpen and playhouse constructed according to an embodiment of this invention.

Figure 2 is a sectional view taken on the line 2-2 of Figure 1.

Figure 3 is a vertical sectional view taken on the line 3-3 of Figure 1, showing the structure converted into a playhouse.

Figure 4 is a fragmentary rear elevation of the device.

Figure 5 is a fragmentary sectional view taken on the line 5-5 of Figure 1.

Figure 6 is a fragmentary front elevation of a slightly modified form of this invention.

Figure 7 is a detail side elevation of another modification of this invention.

Figure 8 is a sectional view taken on the line 8-8 of Figure 7.

Figure 9 is a vertical section through the combined playpen and playhouse shown in Figures 7 and 8 with the structure converted into a playhouse, and

5 Figure 10 is a fragmentary vertical section of the playhouse showing the vertical walls thereof formed as solid walls.

Referring to the drawings, and first to Figures 1 to 5 inclusive, the numerals 15 and 16 designate generally the front and rear playhouse walls, and the numerals 17 and 18 designate generally the side walls of the house. The front wall 15 includes a plurality of horizontally disposed vertically spaced apart log simulating weather boards or 15 side members 19. The side or weather board members 19 are formed with an arcuate outer face 20, which may have the bark of the tree mounted thereon, the siding or weather board members 19 being formed from slabs which are cut from the log of the tree at the time the log 20 is being cut up into boards or other lumber.

At the present time the slabs which are cut from the logs are cut into relatively short lengths, and used as fire wood or for other purposes and 25 are generally considered to be waste material. The slab or siding member 20 is formed with a flat inner face 21 and with a rabbeted edge portion 22 along one longitudinal edge thereof. The opposite longitudinal edge of the siding member 23 may be formed with a tongue as shown at 30 in Figure 10. At the present time, the siding members 19 are spaced apart a distance substantially equal to the width of a siding member so that when it is desired to form a solid front 35 wall 15, additional siding members may be slipped in between each pair of the spaced apart siding members 19.

A lower siding member 24 extends across the lower edge of the front wall 15, and may be of a 40 width substantially equal to or slightly greater than the width of the siding members 19. In the present instance, the lower siding member 24 is shown as slightly wider than the next adjacent siding member 19, and at substantially the longitudinal center of the lower member 24, a cutout or recess 25 is formed within which the lower portion or sill of the door frame is adapted to engage. A vertically disposed post or stud 26 is disposed at one corner of the front wall 15, and 45 is adapted to be secured as by fastening devices 27, in the form of nails or the like, to the outer end portions of the side members 19 and the outer end portion of the lower member 24.

A second post or stud 28 is secured by fastening devices 29 to the siding members 19 on the

opposite sides of the door frame, and the post or stud 28 also engages the rear side and is secured to each rear side of the lower siding member 24. A top rail or plate 30 engages the upper end portions of the posts 26 and 28, and is adapted to be secured to such posts by nails or other suitable fastening devices.

The plate member 30 is formed along the lower edge thereof with a rabbet 31 which extends outwardly from the inner face 32 thereof, and the plate 30 as shown in Figure 1 extends horizontally across the upper edge of the door frame structure. A cornice construction generally designated as 33 is provided for the upper portion of the front wall 15, and includes a pair of outer cornice members 34 and a pair of inner or upper cornice members 35. The cornice members 34 and 35 are of like construction, and are formed with a molding-shaped forward edge or face 36 as shown in Figure 5, which terminates at its lower edge in a flat surface 37 having a groove 38 therein.

The molding member 33 is formed with a flat right angularly disposed rear or inner face 39 and a flat upper face 40. A right angular rabbet 41 is formed at the junction between the flat faces 39 and 40, the purpose for which will be hereinafter described. The upper plate 30, at its upper edge adjacent the opposite ends thereof, is formed with a tongue 42 which engages in the groove 38, and a nail or other fastening device 43 extends through the lower portion of the cornice member 33 and extends through substantially the central portion of the tongue 42. A head plate 44 is disposed in vertical position with the lower horizontal edge thereof contacting with the upper edge of the plate 30 between the two lower cornice members 34, and the upper edge portion of the head plate 44 is disposed within the groove 38 and secured therein by nails or other suitable devices. The configuration of the head plate 44 is such as to provide what is known as a Dutch-roof.

A door frame generally designated as 45 is disposed between the confronting inner ends of the siding members 19, and between the plate 30 and the lower rail 24. The door frame 45 includes a pair of vertically disposed parallel posts 46 which are formed in their outer forward faces with an outer rabbet 47 within which the inner end portions of the siding members 19 are adapted to seat and to be secured by fastening devices 48. The lower end portions of the vertical side frame members 46 are connected together by a lower frame member or sill 49, and the upper end portions of the frame members 46 are connected together by an upper connecting member 50. An upper pair of doors 51 are disposed within the frame 45 being hingedly mounted on hinges 52. The outer edge portions of the door members 51 are adapted to seat in an outer rabbet 53 which is formed in each vertical frame member 46 opposite from the rabbet 47.

A lower pair of doors 54 are disposed below the upper doors 51, being swingedly mounted on hinges 55 which are secured to the rear sides of the vertical door frame members 46. The frame members 46 are formed in their inner sides with a rabbet 56 within which the outer edge portions of the doors 54 are adapted to seat. The upper doors 51 are adapted to swing outwardly to an open position whereas the lower doors 54 are adapted to swing inwardly to an open position.

The rear wall 16 is formed somewhat similar to the front wall 15 being formed of a plurality

of horizontally aligned vertically spaced apart siding members 57 which have convex outer surfaces on which the bark of the tree remains. The outer end portions of the siding members 57 are adapted to be secured by fastening devices 58 to rear corner posts 59 and 60. The back wall 16 may also be formed of a plurality of horizontally disposed vertically spaced apart siding members 61 which extend across the full length of the rear wall 16. A window frame structure generally designated as 62 is disposed between the confronting ends of the short length siding members 57, and the frame 62 comprises a pair of vertically disposed parallel side frame members 63, a lower sill 64, and an upper plate or head 65. The vertical frame members 64 are formed in their outer edges with a rabbet 66 within which the inner end portions of the siding members 57 are adapted to seat, as shown in Figure 2.

The sill or lower rail 64 of the window frame 62 is adapted to engage on the uppermost edge of the long siding member 61, whereas the head plate 65 of the window frame 62 engages against the lower edge of a plate or head member 67 which is secured at the opposite ends thereof to the upper end portions of the posts 59 and 60.

A cornice structure 68, similar in every detail to the cornice structure 33 and shown in more detail in Figure 5, is secured to the plate 67 and also to a head member 69, which extends upwardly from the plate 61. A pair of shutters 70 are hingedly secured on hinges 71 to the window frame 62, and the shutters 70 at their outer portions are adapted to seat in rabbets 72 which are formed in the inner edge portions of the vertical frame members 64. The front and rear walls 15 and 16 may be initially constructed in separate sections or units so that the purchaser of the combined playpen and playhouse may easily and quickly set up the pen and house in the desired location. This combined playpen and playhouse is of fairly small size so that it may be readily set up on a yard, and may be used with or without a foundation, preferably without a foundation.

The cornice structures or rafter plates 33 and 68 have mounted in the rabbeted upper portions 41 and 73 thereof, horizontally disposed parallel shingle strips or roof supporting elements 74. The opposite end portions of the shingle strip or roof supporting elements 74 are adapted to be secured in the rabbets 41 and 73 by fastening devices 75 in the form of nails or the like. The shingle strip or roof supporting elements 74 also provide a means whereby the upper end portions of the front and rear walls 15 and 16 are held in the desired spaced apart relation. It will be understood that if desired, a canvas roof structure may be thrown over the roof supporting elements or strips 74 in order to provide the desired watershed although if desired, any other suitable shingle or roof structure may be mounted on the strip members 74.

The side walls 17 and 18 are adapted to be disposed in outwardly spaced relation with respect to the vertical opposite edges of the front and rear walls 15 and 16 respectively, and initially constitute the outer or side walls of a pair of playpen areas, generally designated as 76 and 77.

The outer side walls 17 and 18 are of like construction and are each constructed of a plurality of edgewise abutting boards 78, which are of a length equal to the distance between the front

and rear end walls 15 and 16. The boards 78 are secured to a pair of vertically disposed corner posts 79 and a plurality of intermediate studs 79a, which are positioned inwardly from the opposite ends of the boards 78. The two posts 79 are spaced inwardly from the opposite ends of the boards 78 a distance substantially equal to the thickness of the end posts 26 and 28 so that when the side wall forming members 17 and 18 are disposed in the positions shown by the dot and dash lines in Figure 2, the posts 49 will substantially abut against the inner vertical faces of the posts 26, 28, 59, and 60. Lower and upper rails 80 and 81 are secured between the posts 79 and to the opposite ends of the studs 60a.

When the side wall forming members 17 and 18 are disposed in outwardly spaced relation with respect to the outer vertical edges of the front and rear walls, the side wall members 17 and 18 are secured to a pair of front and rear fence members generally designated as 82 and 83. The fence member 82 includes lower and upper rails 84 and 85 disposed in parallel relation, and a plurality of spaced apart vertically disposed picket members 86 are secured by fastening devices 87, in the form of nails or the like, to the outer sides of the rails 84 and 85. The lower ends of the picket members 86 may be pointed, as at 88, so as to project a short distance into the surface of the ground in order to hold the combined pen and house structure against movement on the surface of the ground.

The picket members 86 are formed of slabs similar to the siding members 20. The outer end portions of the rails 84 and 85 are adapted to engage against the adjacent outer faces of the vertical posts 79 as shown in Figure 2, and abut against the inner sides of the side forming boards 78 outwardly from the posts 79.

The rear fence or pen member 83 comprises a lower horizontal rail 89 and an upper horizontal rail 90. A plurality of vertically disposed spaced apart parallel picket members 91 are secured by fastening devices 92 to the outer sides of the rails 89 and 90. One vertical edge of each picket 91 is formed with a groove 93 and the opposite vertical edge of each picket 91 is formed with a tongue 94. The picket members 91 are adapted to be used when the pen and house structure is contracted to form only a house as floor boards or the like. The picket members 86 may be used as sheathing for attachment to the longitudinal shingle strips 74.

Referring now to Figure 6, there is disclosed in fragmentary front elevation a slight modification of the combined pen and playhouse wherein the cornice 95 is constructed in inverted V form, as an A roof and a head plate 96 is formed of substantially triangular configuration to conform to the configuration of the cornice 95. In other respects, the structure shown in Figure 6 is similar in every detail to the structure shown in Figures 1 to 5 inclusive.

Referring now to Figures 7 to 9 inclusive, there is herein disclosed a combined pen and playhouse wherein the pen extends rearwardly from the house structure, and the roof portion of the combined pen and playhouse extends also over the pen. The combined pen and playhouse shown in Figures 7, 8, and 9 includes a front wall structure 97, a rear wall structure 98, a pair of side walls 99 and 100, and a pair of pen forming wall members 101 and 102.

The front wall structure 97 is similar in every detail to the front wall structure 15, being formed

of a pair of horizontally disposed slab members 103 which are secured to the outer ends thereof to vertically disposed posts or studs 104. A door frame 105, similar to the door frame 45, is secured to the inner end portions of the short siding members 103, and the door frame 105 is formed of a pair of vertically disposed side frame members 106, which are formed in their outer faces with rabbets 107 within which the inner end portions of the siding members 103 are adapted to seat. A sill or lower frame member 108 is secured between the lower end portions of the vertical frame members 106, and an upper plate or head 109 is secured between the upper end portions of the vertical frame members 106. The frame members 106 in their front faces are formed with rabbets 110 within which a pair of upper doors 111 are adapted to engage. The doors 111 are hingedly mounted on hinge members 112. The inner sides of the frame members 106 are formed with rabbets 113 in which a pair of lower door members 114 are adapted to engage. The door members 114 are hingedly mounted on hinge members 115. The lower door members 114 are adapted to swing inwardly, whereas the upper door members 111 are adapted to swing outwardly.

The rear wall structure 98 is constructed similar in every detail to the rear wall structure 16, being formed of a plurality of horizontally disposed vertically spaced apart slabs 116, which are secured at their outer end portions to vertically disposed posts or studs 117. A rectangular window structure 118 similar in every detail to the window structure 62 is secured in the upper central portion of the rear wall structure 98, and a pair of shutters 119 are hingedly mounted on hinges 120 secured to the frame structure 118.

The shutters 119 are adapted to seat in rabbets 121 formed in the vertical sides of the frame structure 118, and the frame structure 118 is also formed with outer rabbets 122 within which the inner end portions of certain of the slabs 116 are adapted to engage. A cornice structure 123 extends upwardly from the front wall structure 97 and a cornice structure 124 extends upwardly from the rear wall structure 98.

This cornice structure may be formed similar to the cornice structure 33 shown in Figure 1, or if desired, may be similar to the cornice structure 95 shown in Figure 6. A plurality of horizontally disposed spaced apart parallel shingle strips 125 are secured between the two cornice members 123 and 124, and provide a means whereby a suitable roof structure such as a fabric or fibrous roof structure or other suitable roof forming means may be mounted on the strip 125 in order to provide a solid roof for shedding water or preventing the entrance of bright sunlight. Rafters 125a may be secured to the strips 125 rearwardly of the front wall.

The side wall members 99 and 100 are of like construction, and are each formed of a lower rail 126, an upper rail 127 and a rear post or stud 128. Siding members 129 are secured to the outer sides of the posts 128 and the posts and also to intermediate studs 128a. The siding members 129 are similar to the siding members 20 shown in Figure 10, being formed of slabs provided with a rabbet in one edge thereof, and a tongue in the other edge so that if desired, the vertically spaced apart siding members 129 may have additional siding members inserted therebetween to form a solid side wall structure. A pipe 130 may be secured

between the upper rails 127 to support a swing or the like.

A playpen area 132 is disposed rearwardly of the rear ends of the side wall members 99 and 100, and in the initial formation of the combined pen and playhouse the playpen area 132 is disposed inwardly from the rear wall 99 which forms the rear wall of the playpen area 132. The siding members 101 and 102 form with the rear wall 98 a three-sided playpen area which has initially the rafter members 125 extending over the upper portion thereof. The pen side wall 102 is formed of upper and lower parallel rails 133 which, at their forward ends, are adapted to abut against the stud 128 and may be secured to the projecting end portions of the weather boarding members 129. The rear ends of the rails 133 engage against the outer side of the vertical posts or stud 117 and abut at their rear ends against the inner faces of the rear siding members 116.

A plurality of vertically disposed parallel spaced apart picket members 134 are secured to the outer sides of the rails 133 and each picket member 134 is formed in one vertical edge thereof with a groove 135, and in the opposite vertical edge thereof with a tongue 136. The picket members 134 are adapted to be subsequently used as floor boards which may be secured to the rails 126 of the side wall members 99 and 100.

The pen wall member 101 is constructed of a pair of vertically spaced apart parallel rails 131 which abut at their forward ends against the adjacent stud or post 128 carried by the side wall member 99, and the rear ends of the rails 131 engage against the outer side of the adjacent rear stud member 117 opposite from the pen wall 102. The rear ends of the rails 131 abut against the inner faces of the adjacent siding members 116 as shown in Figure 8.

A plurality of vertically disposed spaced apart picket members 138 are secured to the outer sides of the rails 137, and preferably the picket members 138 are substantially rectangular in transverse section, as shown in Figure 8, so that these picket members may subsequently be used to provide the material for forming at least a portion of the roof sheathing to be secured to the roof rafters 125a.

In the construction and use of the combined playpen and playhouse, shown in Figures 1 to 6 inclusive, the end walls 15 and 16 may initially be constructed as a unit, and the side walls 17 and 18 also constructed as a unit. The walls 82 and 83 of the playpen forming sections, are also adapted to be constructed as a unit so that the entire structure may be constructed at the factory in knock-down form, so that the purchaser and user of the device may easily and quickly assemble and set up the device in the desired portion of the yard or the like.

Where the purchaser of the device desires to make use of the playpen areas, the structure may be set up as shown in Figure 2. However, if at a later date it is desired to eliminate the playpen area and to form a playhouse which may have the front and rear walls thereof formed either solid or open, the side walls 17 and 18 may be moved inwardly to contact with the adjacent edge portions of the front and rear walls, and may be secured to the studs or posts 26, 28, 59, and 60. The rails to which the pickets 86 and 91 are secured may be removed from the pickets and secured between the contracted rails 80 of the side wall members 17 and 18. The picket members 86 may be cut off at their lower ends to

remove the points 88 and may then be used as sheathing for attachment to the rafters 74.

The tongue and groove pickets 99 may be secured to the floor beams which include the rails 80 and the reset rails from the pen, forming walls 82 and 83. The number of floor forming pickets 91 may not be sufficient to form a solid floor so that the floor of the contracted playhouse structure may have open spaces therein, although if desired, additional tongue and groove boards may be used to provide the necessary solid floor.

The combined playpen and playhouse structure shown in Figures 7, 8, and 9 may also be constructed in sections, and if desired, this structure may be formed with the front and rear walls 97 and 98 in individual sections and with the side wall 99 formed with the adjacent side 101 of the pen area. The side wall 100 may also be formed as a unit with the wall member 102 of the adjacent side of the pen area. The roof rafters 125 are initially in loose form, but of desired length so that the purchaser of the knock-down house may easily and quickly assemble the several sections to provide the desired building.

What is claimed is:

1. A combined playpen and playhouse comprising front and rear walls, each wall including a plurality of vertical studs, a plurality of horizontally disposed vertically spaced apart slab members simulating logs secured to said studs, a substantially V-shaped cornice structure and a head plate secured to said cornice structure and extending upwardly from the uppermost of said slab members, a pair of vertically disposed side walls disposed in laterally spaced relation with respect to the vertical edges of said front and rear walls, and a pair of picket elements interpose between each side wall and the adjacent edges of said front and rear walls whereby to form with said side walls a pair of playpen areas outwardly from the opposite vertical edges of said end walls the slabs forming the front and rear walls of said playpen adapted to be removed and inserted in the spaces between the slabs forming the front and rear walls of said playhouse, to thereby form closed front and rear walls for said playhouse.

2. A combined playpen and playhouse comprising front and rear walls, each wall including a plurality of vertical studs, a plurality of horizontally disposed vertically spaced apart slab member simulating logs secured to said studs, a substantially V-shaped cornice structure and a head plate secured to said cornice structure and extending upwardly from the uppermost of said slab members, a pair of vertically disposed side walls disposed in laterally spaced relation with respect to the vertical edges of said front and rear walls, and a pair of picket elements between said side walls and the vertical edges of said front and rear walls, the pickets of said elements being removable for positioning between the slabs of said front and rear walls to thereby form a substantially closed playhouse.

3. In combination a playhouse comprising front and rear walls formed of spaced apart slabs and constructed in sections, a playpen on either side of said playhouse, said playpen being constructed of spaced apart slabs, and means whereby said latter slabs may be used to entirely close the front and rear walls of said playhouse, closed side walls for said playpen, said side walls being so constructed as to be used as the side walls

of said playhouse when it is desired to use the structure as a closed house.

4. In combination a knock-down playpen and playhouse constructed in sections and including individual front and rear wall sections, and a pair of individual side wall sections, said side wall sections adapted to form the sides for the playpen, and alternately to be used as the sides of said playhouse, a roof over a portion of said structure, each front and rear wall section including a plurality of studs, and a plurality of spaced apart slab members secured to said studs, the slabs forming the front and rear walls of the playpen portion of said device adapted to be removed and subsequently inserted in the spaces between said playhouse slabs, to thereby form closed front and rear walls to said playhouse.

5. In combination, a playpen formed of spaced apart slabs constituting the front walls thereof, a playhouse formed of spaced apart slabs constituting the front walls thereof, the slabs from said playpen adapted to be removed and fitted in the spaces between said playhouse slabs to thereby form closed front wall therefor, said playpen having closed side walls adapted to be converted into side walls for said playhouse, longitudinal rafters on said playhouse on which a covering may be placed to thereby form a roof for said playhouse.

6. A combined playpen and playhouse structure including front and rear walls, each wall including a plurality of vertical studs, a plural-

ity of horizontally disposed vertically spaced apart slab members simulating logs secured to said studs, a substantially V-shaped cornice structure and a head plate secured to said cornice structure and extending upwardly from the uppermost of said slab members, a vertically disposed side wall disposed in laterally spaced relation with respect to the adjacent vertical edges of said other walls, and picket elements between

10 said side wall and the said vertical edges of said other walls, the pickets of said elements being removable for positioning between the slabs of said front and rear walls to thereby form a substantially closed playhouse.

15 7. In combination a knockdown playpen and playhouse constructed in sections and including individual front and rear wall sections, and a pair of individual side wall sections, either side wall section adapted to form a side for the playpen and alternately to be used as a side of said playhouse, and a plurality of slabs forming the front and rear walls of the playpen, each front and rear wall section including a plurality of studs and a plurality of spaced apart slab members secured to said studs, the slabs forming the front and rear walls of the playpen portion of said device adapted to be removed and subsequently inserted in the spaces between said playhouse slabs, to thereby form closed front and rear walls to said playhouse.

SAMUEL L. DENNIS.
